CLAIM

The ornamental design for an abdominal exerciser bench, as shown and described.

DESCRIPTION

The present invention is also related to U.S. Design patent application Ser. No. 29/508,540, filed on Nov. 7, 2014.

FIG. 1 is a perspective view showing the new design for an abdominal exerciser bench;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

(Continued)

The broken lines depict elements of the article that form no part of the claimed design.
